UNITED STATES PATENT OFFICE.

LOUIS J. HANHART, OF CINCINNATI, OHIO, ASSIGNOR TO THE J. A. FAY & EGAN COMPANY, OF SAME PLACE.

SAWING-MACHINE.

SPECIFICATION forming part of Letters Patent No. 659,475, dated October 9, 1900.

Application filed June 4, 1900. Serial No. 19,048. (No model.)

To all whom it may concern:

Be it known that I, LOUIS J. HANHART, a citizen of the United States, residing at Cincinnati, in the county of Hamilton and State 5 of Ohio, have invented certain new and useful Improvements in Sawing-Machines, of which the following is a specification.

My invention relates particularly to that class of sawing-machines used for ripping 10 and edging stock, and has for its object the providing of new and convenient means for the manipulation, adjustment, and setting of the parts.

My invention consists in providing a novel, 15 substantial, and convenient means for supporting and manipulating the outer bearing of the saw arbor or shaft on a machine of this character, so that the same may be easily dropped into a position clear of the saw-blades, so as to permit the removal of the latter and insure its being returned to proper 20 position with a minimum amount of exertion and care, in the novel means provided for setting the saw-blades and insuring accuracy 25 in the cut, and in the parts and in the construction, arrangement, and combinations of parts hereinafter more fully described and claimed.

In the drawings, Figure 1 is a plan view 30 of my improved device with the middle of the feeding-frame containing the usual idler-rolls and side gages broken away, as these parts are old and will be readily understood by those skilled in the art, with the in-feeding 35 upper roll also broken away and the pulleys on the lower feed-roll shafts shown broken. Fig. 2 is a side elevation of the saw-supporting part of the frame with the outer arbor-bearing bridge-tree also shown in depending 40 position in dotted lines. Fig. 3 is a side elevation of the saw-blade-setting and tension-adjusting mechanism, showing only so much of the frame as to indicate its connection therewith. Fig. 4 is a plan detail of the saw-blade-shifting guide. Fig. 5 is a side elevation 45 of the same with the swinging part thereof also shown in assumed position in dotted lines. Fig. 6 is a plan detail of the tension-adjusting mechanism for the saw-blade-shifting device. Fig. 7 is a detail in horizontal cross-section of the saw-blade-shifter-locking

mechanism. Fig. 8 is a side elevation of the saw-blade-shifter-locking mechanism shown in connection with the shifter-wheel, the latter shown broken. Fig. 9 is a detail showing 55 the movable bearing and bridge-tree for the saw-wheel arbor in its normal position with relation to its adjacent parts and also showing it in assumed position in dotted lines.

A represents the frame, in which a saw arbor or shaft B is journaled in bearings C C, with an outer bearing D also provided in the manner hereinafter described. The saw-arbor has a series of saw-blades E secured thereto in such manner as to revolve with the arbor to perform the cutting operation, but arranged to slide on the arbor, as by means of having a hub for the blade with a spline connection to the arbor, in any ordinary and well-known manner. The saw-arbor is turned 60 from a suitable source of power by a pulley 1. It also carries a second pulley 2, which by means of a belt passing thereunder and over pulleys 3 4 on shafts 5 6 operates lower feeding-rolls 7, one at each side of the saw- 65 arbor, a tightener being provided for the belt, as indicated at 8. Upper feed and pressure rolls 9 10 are hung in housings 11 12, pivoted on a rod 13, the descent of the rolls being limited by having lugs 14 on the housings 70 strike the frame. The upper rolls may be adjusted to height by having ropes or rods take into eyelets 15 in the housings, the housings being suspended by the rods or ropes. The saw-blades in a machine of this character 75 are frequently changed, larger or smaller blades or blades provided with differently set or swaged teeth being placed upon the arbor to accommodate for different thicknesses or classes or kinds of stock, it being also necessary to frequently remove the blades for the purpose of resharpening and kindred operations. I provide means for readily allowing this removal and replacement in a highly-efficient, economical, and simple manner. 80 The saw-guides are first turned out of the way of the blades in a manner to be herein-after described, leaving the saw-blades free 85 to be readily slipped along the length of the mandrel to the outer bearing D. The side of 90 the frame toward which the blades are thus slipped is provided with a large, preferably 95 100

2

circular, opening 21 to permit the blades being slipped therethrough. The outer bearing D is mounted on a web or bridge-tree 22, slipping sidewise upon shafts or rods 23 24, 5 upon which the bridge-tree is also secured by means of set-screws 25. The ends of the bridge-tree preferably form bearings 26 27 to take over the rods. One of the rods, as 10 24, is lengthened, as shown more clearly in Figs. 1 and 9, so that the bearing D and bridge-tree may be slipped sidewise until the bearing has cleared the saw-arbor, as indicated in dotted lines in Fig. 9, and is then permitted to swing downwardly on the 15 rod to vertical position, as indicated in dotted lines in Fig. 2, where it remains until the saws have been given attention. In this way the full weight of the bridge-tree and bearing is never supported by the operator 20 or operators removing the saw-blades, but only sufficient exertion is needed to slide the bridge-tree sidewise on the rods until the bearing clears the saw-arbor, when it is permitted to drop on the rod to hanging position. 25 A shoulder 28, secured to the end of the rod by a screw 29, prevents the accidental slipping of the bridge-tree off the rod. After the blades have been given attention and it is desired to return the bearing the bridge-tree 30 is simply returned to horizontal position by swinging the same pivotally about the rod until the bearing D and the saw-arbor and the other end bearing of the bridge-tree and its rod are in line, when the bridge-tree is 35 slipped sidewise, no great care being required to connect the parts, the connections being very easily and conveniently brought into line, and no great strength or exertion being required to bring the parts to position for 40 connection. After the bridge-tree is in place the set-screws 25 are screwed up.

The shafts or rods 23 24 preferably extend transversely across the machine-frame, so as to give stability and so that one of them may 45 form a support for the saw-blade guides F F' F². The guides F F' connect with the saw-blade-adjusting mechanism hereinafter described. The guide F² connects with a third rigidly-set blade. The guides comprise, preferably, two parts 31 32. The part 31 has a sleeve 33 taking about the shaft, say 23. It extends forwardly and has a finger 34 extending upwardly in front of an index-plate 35 to indicate the position of the saw-blade to the 50 operator standing at the feeding-in end of the machine. The finger 34 takes over and the forward end of the part 31 takes under a transverse guide 36 to guide the part in its transverse sliding and to give it stability. 55 The part 32 is bifurcated, with the saw-blade arranged to take into the bifurcation. Each prong or side is provided with a block 37 for taking against the side of the saw-blade. A bearing 38 is provided for the part, upon 60 which it swings about the sleeve 33. A collar 39 prevents sidewise movement with rela-

tion to the sleeve. A lug 40 on the part 31 takes under the part 32 and limits the descent of the latter piece. When it is desired to remove the saw-blade, the part 32 is swung 70 on its pivot so as to clear the saw-blade, as indicated in Fig. 5, which permits the blade to be slid upon its shaft past the guide. The part 32 has a clamp 41, to which a cord, cable, rope, or the like 42 may be secured, as in an 75 opening 43. Each movable guide is preferably provided with a rope 42, and an opening 44 permits the ropes of another guide to pass a given guide.

The guides are shifted by means of hand-wheels 46, of which I have shown two, preferably one for each movable saw-blade. Each hand-wheel connects with a shaft 47, carrying at its end, adjacent to the saw-blades, a sheave or drum 48, to which the ends of the rope 42 80 are secured. Each rope forms a loop beginning at the sheave 48, extending about an end sheave 49, mounted on a shaft 50 in lugs 51 on the frame, thence extending across the frame to another side sheave 52. Intermediate of this extension across the frame the guide is attached to the rope in the manner already explained. From the last-named sheave the rope extends to the sheave 48, to which its other end is fastened. The end 95 sheaves are mounted side by side, the sheaves 49 preferably stationary. Openings 55 are left in the frame at each side to accommodate the sheaves. Each of the sheaves 52 is mounted in a yoke 56 on a short shaft or pin 57, the outer end of the yoke having an adjusting-screw 58 collared thereto, which adjusting-screw takes through an internally-threaded aperture in a yoke 60, attached to the side of the frame opposite the opening 55. The adjusting-screw takes up all slack and lost motion in the rope and connected parts, so that the finger may always truly and accurately indicate the position of the saw-blade and that the saw-blade may be accurately brought to 100 position from the hand-wheel.

The inner side of the hand-wheel is provided with a number of notches or indentations 61, corresponding in distance apart to the markings on the index-plate—as, for instance, inches. The frame adjacent to the hand-wheel is provided with a plunger 62, adapted to take into the notches. The plunger takes into a bearing 63 and has a reduced shank 64, forming a shoulder 65, between 115 which and the bearing a spring 66 takes about the plunger, forcing the latter outwardly. The end of the reduced shank slides in a guideway 67. The outer end of the plunger is preferably conical, as shown at 68, the notches 120 61 being similarly shaped. A pin or contact face 71 extends from the plunger preferably through a slot 72 in the bearing. A trigger or stop 73 is secured to the bearing, as on a pivot 74, and preferably has an inclined face 130 75 to take against the pin on the plunger, thereby wedging or forcing the plunger into

its notch and firmly securing the hand-wheel with relation to the frame and the saw-blade with relation to its arbor and the frame.

In setting the saw-blade the trigger or stop 5 is raised so as to allow the plunger to be forced back and allow the notches in the hand-wheel to pass the plunger, and when the saw-blade is set the trigger is thrown against the pin and the hand-wheel thereby locked, as 10 previously explained, thereby also locking the saw.

As before stated, the notches in the hand-wheel into which the plunger takes register with the markings on the index-plate 35. It 15 is sometimes difficult to determine the exact position of the finger 34 with relation to the markings on the index-plate from the operator's position at the feeding-in end of the machine, which may be distant ten to twenty 20 feet from the index-plate; but when the plunger takes into the notch the operator knows that the point of the finger registers with the mark on the index-plate, and the conical end of the plunger being forced into and locked 25 in the notch takes up any variation there may be between the finger and mark on the index-plate and locks the saw-blade in its proper position for cutting to exact size.

By means of my improved arrangement 30 when locked all of the parts are firmly and rigidly secured with relation to each other, with all lost motion taken up.

My device is very simple and economical in construction and operation, it has few 35 parts, is very durable and not likely to get out of order, all lost motion is readily taken up, the parts after adjustment are arranged to be securely locked with relation to each other by simple mechanism to present a firmly- 40 united structure rigid in all its parts, and exceedingly ready and handy in manipulation.

I claim—

1. The combination, in a machine of the character described, of a frame, a saw-arbor 45 mounted therein, a series of saw-blades, slidably secured to the arbor, an outer bearing for the arbor, a bridge-tree for the bearing slidably sidewise longitudinally of the arbor, means for supporting the bridge-tree independent of the arbor with relation to the frame and permitting the sliding sidewise of the bridge-tree and the swinging thereof away from the arbor while attached to the frame, substantially as described.

2. The combination, in a machine of the character described, of a frame, a saw-arbor mounted therein, a series of saw-blades, slidably secured to the arbor, an outer bearing for the arbor, a bridge-tree for the bearing 50 slidably sidewise longitudinally of the arbor, with a stop for the bridge-tree, means for supporting the bridge-tree independent of the arbor with relation to the frame and permitting the sliding sidewise of the bridge-tree 55 and the swinging thereof away from the arbor while attached to the frame, substantially as described.

3. The combination, in a machine of the character described, of a frame, a saw-arbor journaled therein, an outer bearing for the 70 arbor, a bridge-tree for supporting the bearing, and a rod for supporting the bridge-tree, and constructed and arranged for moving the bearing and bridge-tree sidewise longitudinally of the arbor until the bearing clears the 75 arbor and then swingingly lowering the bearing on its bridge-tree while supported by the rod, and means for fastening the bearing and bridge-tree in operative position, substantially as described.

4. The combination, in a machine of the character described, of a frame, a saw-arbor, a saw-blade slidably supported by the arbor and turning therewith, a guide-piece for the saw, a shifting-shaft for the same, a hand-wheel for the latter, with notch-and-plunger mechanism between the hand-wheel and frame, inclined faces between notch and plunger, a contact-face for the plunger, and a stop for the contact-face locking the plunger and hand-wheel stationary with relation to the frame and the saw-blade in position on the arbor, substantially as described.

5. The combination, in a machine of the character described, of a saw-arbor, a saw-blade slidably supported by the arbor and turning therewith, a guide-piece for the saw, a shifting-shaft for the same, a frame in which the same is journaled, a hand-wheel for the shaft, a finger, and an index-plate, with 95 notches and a plunger, a spring for the plunger, inclined faces between the plunger and the notches, a contact-face for the plunger, and a positive lock, having a cam-face, for taking against the contact-face for seating 105 the inclined faces with relation to each other and thereby relatively centering the finger and a mark on the index-plate and locking the saw-blade in its proper position for cutting to exact size, substantially as described.

6. The combination, in a machine of the character described, of a saw-arbor, a series of saw-blades slidably supported by the arbor and turning therewith, side contact-pieces for the blades, a finger, an index-plate, a saw-blade-shifting shaft with a sheave therefor, a sheave to each side of the saw-blades, a rope or similar device taking about the latter sheaves and attached to the former sheave, means for adjusting the position of a side 115 sheave for taking up lost motion, a hand-wheel for the feeding-in end of the shifting-shaft, a series of notches in the hand-wheel and a plunger for taking into the same, with a contact-face for the plunger and a movable 120 stop for the contact-face, constructed and arranged to indicate the position of the saw-blade with relation to a mark on the index-plate and to center and positively lock the saw-blade in position at that mark, substantially 125 as described.

7. The combination, in a machine of the character described, of a frame, a saw-arbor journaled therein, a series of saw-blades slid-

able on the arbor, an outer bearing for the arbor, a bridge-tree for the bearing, a rod on which the bridge-tree is pivotally hung extending longitudinally beyond the arbor and 5 arranged for first sliding the bridge-tree side-wise longitudinally of the arbor and then swingingly away from the arbor to permit the removal of the saw-blades, side contact-faces for the blades, adjusting-shafts for the contact-faces, a hand-wheel for the adjusting-shaft, a series of notches in the hand-wheel, 10 a plunger taking into the notches, a contact-face for the plunger, a stop for the contact-

face, and constructed and arranged for rigidly securing the hand-wheel with relation 15 to the frame and the saw-blade on its arbor by the contact of the stop with the contact-face for the plunger, substantially as described.

In testimony whereof I have signed my 20 name hereto in the presence of two subscribing witnesses.

LOUIS J. HANHART.
